UNITED STATES PATENT OFFICE

WILLIAM H. SCOTT, OF ROCHESTER, NEW YORK

FILLING AND DRAINING DEVICE

Application filed June 4, 1929. Serial No. 368,343.

The present invention relates to filling and draining devices and more particularly to the type in which an ejector is provided with two faucet connections, both of which may be connected to two faucets when filling a receptacle, and one being connected with a faucet while the other acts as a discharge when draining a receptacle. An object of this invention is to provide an outer splash attachment for the faucet connection which acts as a discharge when draining a receptacle. Another object of the invention is to provide an attachment which will permit filling and draining devices of the class described to be employed as self starting siphon tubes.

To these and other ends, the invention consists of certain parts and combinations of parts all of which will be hereinafter described: the novel features being pointed out in the appended claims.

In the drawings:

Fig. 1 is a view showing the device mounted to drain a receptacle into a sink; the dotted lines showing the filling adjustment;

Fig. 2 is a view showing the device adjusted to act as a self starting siphon; and

Fig. 3 is an enlarged central section of the ejector casing.

In the illustrated embodiment of the invention there is employed a casing having three arms 1, 2, and 3, the first being the intake for the ejector formed by a wall 4 with a restricted opening 5 discharging into the discharge arm 2 which, in this instance, is aligned with the ejector. The other arm 3 extends laterally from the casing between the discharge 2 thereof and the ejector so that water passing through the ejector will draw water in through the arm 3 to mix with the water passing from the ejector.

The ejector arm 1 has a faucet connection connected thereto, in this instance, an internally threaded collar 6 journaled on the arm forming the ejector. The discharge arm also has a faucet connection connected thereto preferably in the form of a flexible tube having an internally threaded collar 8 journaled on its free end. To the arm 3 is con-

nected a flexible tube 9 which is preferably longer than the tube 7.

For filling a receptacle the two faucet connections are secured to two faucets and the tube 9 is placed in the receptacle 10 to be filled as shown in dotted lines in Fig. 1. Both faucets are turned on and the water therefrom flows into the receptacle.

For draining a receptacle the faucet connecting means connected with the arm 2 is permitted to lie in the sink 11 while the faucet connecting means connected with the ejector arm 1 is connected to a faucet. The tube 9 is placed in a receptacle 10. The turning on of the faucet causes the water passing through the ejector to draw water from the receptacle 10 through the tube 9 and discharge such water with that passing through the ejector into the sink 11.

It has been found that the water discharged through the tube 7 in draining a receptacle tends to produce a splash from the sink and to prevent this action there has been provided an anti-splash device which detachably connects with the faucet connecting collar. In this instance, this anti-splash device comprises a cup shaped member 12 formed of rubber and having an externally threaded nipple 13 at one end for detachable connection with the internally threaded collar 8. This cup shaped member is placed over the drain 14 in the sink 11 and conducts the water to the drain without any splashing.

The cup shaped member 12 may also be employed for creating a suction in the device for the purpose of using the device as a siphon. As, for instance, shown in Fig. 2 for draining a receptacle 14^a into a receptacle 10^a. When so used a screw plug 15 is fitted into the internally threaded collar 6 to close off the ejector. Pressure on the bottom of the receptacle 10 by the cup 12 creates a suction which will start water through the device and this will continue so long as the level in the discharging receptacle 14^a is above the water level of the receiving receptacle 10^a.

It will thus be seen that the flexible detachable cup has two functions in connection with a device of this kind. It serves 100

as an anti-splash device and also as a suction creating device for obtaining a siphonic action.

What I claim as my invention and desire to secure by Letters Patent is:

- 5 1. The combination with an ejector, of two faucet connecting devices connected to the ejector, one at the intake end the other at the discharge end, a third conduit leading from the ejector at the discharge end and through which water may be drawn by water passing through the ejector, of a suction device carrying means detachably interlocking with that faucet connecting device which connects with the discharge end of the ejector.
- 10 2. The combination with an ejector having a faucet connecting device connected to the intake thereof, and two fluid conductors connected to the ejector on the discharge side thereof, one of said conductors having its inner end so disposed with reference to the ejector that the liquid is drawn therethrough and discharged through the other conductor, a faucet connecting device connected to the free end of the discharging conductor, and a cup shaped device having a device detachably but rigidly interlocking with the second mentioned faucet connecting device, said cup shaped device being adapted to be held by suction over the drain of a sink, whereby the water is forced under pressure through the drain to prevent clogging of the same.
- 15 3. The combination with an ejector having a faucet connecting device connected to the intake thereof, and two fluid conductors connected to the ejector on the discharge side thereof, one of said conductors having its inner end so disposed with reference to the ejector that the liquid is drawn therethrough and discharged through the other conductor, a closing device for the ejector detachably interlocking with the faucet connecting device, and a flexible cup shaped suction member rigidly connected to the free end of the discharging conductor.

WILLIAM H. SCOTT.
